REHEAT SUPERHEATER

Application filed February 1, 1926. Serial No. 35,090.

Our present invention relates to steam re-heaters and will best be understood from the following description and the annexed drawings, in which Fig. 1 is a vertical section of an illustrative embodiment of our invention with the well understood lower portion of the steam generator broken away; Fig. 2 is a transverse section of a portion of Fig. 1; Fig. 3 is an enlarged side view of one of the details; Fig. 4 is a section taken along the line 4—4 of Fig. 1; Figs. 5, 6, and 7 are enlarged side views of details.

In the drawings, the upper portion of a known type of steam generator is shown, having horizontally inclined water tubes 10 connected to uptake headers 11 which, in turn, are connected through steam and water circulators 12 with a steam and water drum 13, this latter being connected by downtake nipples 14 with the downtake headers to which the lower ends of the tubes 10 are connected. A superheater 15 is shown above the tubes 10 through which the steam generated by the heater is passed and superheated. The steam from the superheater 15 is led to the main steam line which supplies steam to the steam turbine. The waste gases from the steam generator, after passing over the tubes 10 and the superheater 15, flow upward through a vertical flue 16, separated by a wall 17 from a second vertical flue 18 which carries the gases down over tubes 12 and between the nipples 14 to the boiler gas exit. The front wall 17^a is provided with openings 17^b across the vertical flue 16 to permit cold air to mingle with the hot gases for the purpose of controlling the temperature of the reheated steam in the re-heater tubes and preventing it from rising above a predetermined point.

The rear wall 19 is inclined so as to produce a progressively narrowing pass as the gases flow downward through the flue 18, and this wall is provided with doors 19^a, 19^b and 19^c for purpose to be described more fully hereinafter.

Adjacent the lower portion of the flue 18 and near the wall 19 is an inlet manifold 20, to which an inlet steam pipe 21 is connected. Similarly, at the upper portion of the flue 18 is a steam outlet manifold 22, to which

a steam outlet pipe 23 is connected. Between the manifolds 20 and 22 is a supplemental manifold 24.

All of the steam from an intermediate stage of the steam turbine flows through the inlet steam pipe 21 and thence through the tubes of the re-heater and after the temperature of the steam is raised the desired amount through the reheating, it passes outward through the steam outlet pipe 23 to the next succeeding stage of the steam turbine. It is essential that in passing the steam from the steam turbine and returning it thereto that there be a minimum drop in the pressure on account of the friction of the steam flowing through the piping and the re-heater, otherwise the thermodynamic gain due to the reheating of the steam may be entirely offset by the loss in power generated by the steam turbine. In the re-heater of this sort it is, therefore, very advantageous for the steam to pass through it with a minimum amount of resistance.

The manifolds 20, 22 and 24 are connected by tubes, so that steam entering the manifold 20 will flow in a generally upward direction to the outlet manifold 22 while the heating gases are flowing downward. It is important to have the steam flow upwardly through the heating tubes in order to secure an even distribution of the steam between the different tubes of the re-heater with a minimum resistance to flow. Should the steam from the steam turbine be led into the uppermost header and be discharged from the lowermost header of the re-heater so as to cause the steam to flow downwardly, there would be a tendency to stagnate the flow of the steam through some of the tubes which would reduce the efficiency of the re-heater and might result in the burning out of the tubes. With a downward flow should one or more tubes become hotter than the others the density of the steam in these tubes would become less than that in the remaining tubes and the statical head produced through the change in density would tend to retard the flow of the steam through the tubes which are overheated. With an upward flow any overheating of the tubes would tend to in-

crease the flow of steam through the tubes through this same cause and would tend to prevent overheating.

In the illustrative embodiment, the manifolds 22 and 24 are connected by a plurality of U-tubes 25, such tubes extending transversely of the flue 18 and preferably being long enough so that they will be supported on the top of the wall 17 and will also extend 10 into the flue 16.

The manifolds 20 and 24, in the illustrative embodiment, are connected by a plurality of U-tubes 26 which are given a number of reverse bends with the substantially horizontal 15 leg portions of the tubes transverse of the flue 18 and of progressively shorter length.

By making the length of the transverse portions of the superheater tubes as illustrated, we not only are able to form the flue 18 20 so that it will give a mass flow increase to improve heat transfer rate per degree difference in temperature as the gases flow through the flow, but also we are able to provide the greatest amount of superheating surface at 25 the point where the gases are hottest and just before the steam leaves the superheater.

The wall 19 is provided with a door 19^a large enough to permit the insertion and withdrawal of the tubes 25 and the corresponding door 19^b permits the insertion and withdrawal of the tubes 26.

A transverse supporting girder 28 extends through the boiler from side to side of the setting. This girder is made hollow, to provide air ventilation for cooling it. The girder is shown as made up of I-beams 29 and 29' to form the side walls and cross pieces 30 and 30' to form the top and bottom thereof. A Z-bar 31 and an angle-bar 32 may be attached to one side of the girder, and metal plates 33 (Figs. 1 and 5) may be suspended by means of hooks 34 from these Z- and angle-bars. The plates 33 are made up of vertical portions 35 and sloping portions 35', one side 40 of these plates being provided with bulbed ribs 36 for holding tile in the well-known manner, by providing grooves in the tile which slip over the bulbed portions of the ribs. The sloping portions 35' are provided 45 with strengthening ribs 37, and ledges 38 extend outwardly from the other side near the lower ends of the plates, upon which ledges tile guided by the bulbed ribs 36 may rest. A transverse plate 39 extends across 50 and is attached to the lower ends of the plates 33, as by bolts or rivets, and is provided with recessed rounded portions to receive the upper row of tubes 12. A plate 40 with slots 55 along its edges to receive the tubes 12 is attached along one edge to the plate 39, and along the other edge to the angle iron 41 which is, in turn, attached to the plates 42 that are provided with horizontal extensions 42' for sustaining wall tile, and a vertical 60 portion 43 which extends across the tubes 15

to the upper edge of the baffle 44, which baffle is provided with a by-pass door 45 for short circuiting the hot gases to the stack. The by-pass door 45 is operated as a safety measure when the steam turbines are shut down to 70 prevent burning of the reheat tubes 25 due to lack of steam passing therethrough.

Suspension rods 48 provided with turn buckles 49 are attached to the girder 28 and are fastened to lugs provided on the header 75 50 of the superheater 15, so as to support this header.

A Z-bar 51 and an angle-bar 52 are attached to the girder 28, and plates 53 are suspended therefrom by means of hooks 54. These plates 53 are provided with channeled ribs 55 (Figs. 1 and 7), the upper ends of which are connected by means of angle irons 56 to the bar 57, upon which the bottom row of tubes 26 rests, so that these tubes are supported by the channel 28. Plates 58 (Figs. 1 and 6) provided with inturned ends 59 may be attached by these inturned ends to the plates 53, and the lower ends of these plates may be attached to the upper edge of 80 the plate 39 on the side opposite the plates 35. 85

A metal cross bar 61 (Figs. 1, 3 and 4) extends across the lower side of the tubes 26, parallel with the bar 57, and a similar bar 62 extends across the topmost sides of the lowest 90 horizontal portions of the tubes 26. The bars 61 and 62 are connected by metal members 63 and 64 which cross each other (Fig. 3), and are provided with recesses 65 to accommodate the tubes 26. The bar 62 is connected by means of metal plates 66 to a similar bar 61 extending across the lower side 95 of the next horizontal portions of the tubes. In this way a wall of considerable compressive strength is built up entirely across the successive horizontal portions of the tubes 26, and sustains or supports their intermediate portions. A similar wall is built across the tubes 25 by means of the bars 61', 62' and 100 plates 63', 64' and 66', the two walls being 105 spaced apart a short distance in vertical planes, so as to permit gas to pass between the two at this spaced section. Another similar wall may be made across the tubes 25 above and resting upon the wall 17 by means 110 of the bars 61'', 62'' and plates 63'', 64'' and 66'' so as to direct the gases across the bends of these tubes and also help support the tubes. The supporting girder 28 not only supports 115 the walls 17 and metal plates 33 and 42 with their tile but also the header 50 as well as the plates 53 which, in turn, support the tubes 26 as above described.

The roof 70 above the two flues 17 and 18 may be of any desired construction. In the arrangement shown, the refractory bricks 71 are suspended from the beams 72 by bolt hangers 73, so that the bricks 71 may be free 120 to expand without injury.

The structure which we have disclosed 130

may be used either as a superheater for superheating steam from the boiler or it may be used, as in the illustrative arrangement, for reheating steam between stages of a multi-stage prime mover, and it will be understood that when we use the term "superheater" in the appended claims, we mean either a primary superheater or a superheater for re-superheating exhaust steam.

10 It will also be understood that our invention may be embodied in various forms and that the arrangement which we have shown is merely illustrative.

15 The reheat superheater described in this specification is especially adapted for use in connection with steam turbines that are connected in tandem or in which interstage reheating of steam is accomplished after it passes through one turbine or stage and before it enters the next succeeding turbine or stage. It is to be understood that this reheat superheater is suitable for use in connection with other boilers that supply steam to the first turbine which may be supplemented by steam supplied by the steam generating and superheating tubes or boiler proper, indicated in the lower portion of Fig. 1. The requirements for such reheat superheaters differ materially from those for ordinary boiler superheaters. Such reheat superheaters should receive a very large fraction of the heat from the boiler furnace because the primary object of a boiler equipped with such reheat superheaters is not to produce steam but to superheat steam already produced. To keep the superheat high and constant enough for advantageous use, it is necessary to control the fire for superheat and not for steam making. In a boiler equipped with a reheat superheater the ratio of steam superheated to steam generated is always much greater than unity, whereas in ordinary boilers with superheaters, the ratio is exactly unity. Consequently the reheat superheater absorbs a much greater proportion of the total heat than the ordinary boiler superheater absorbs. We have obtained excellent results, for example, by making the reheat superheater of such a size and character that it absorbs approximately 40% of the utilized total heat from the furnace of the boiler in which it is located, while about 8% is absorbed by the regular boiler superheater and the remainder by the boiler tubes proper. In a standard superheater boiler about 87% of the utilized heat is absorbed by the boiler proper and 13% by the boiler superheater. Another difference in a reheat superheater is with respect to the relative amounts of hot gases used per pound of steam compared to that used in a regular boiler. In a standard boiler about 1.5 to 1.8 pounds of gas is required per pound of steam generated, and in a reheat boiler about 2.5 to 3 pounds of gas are required per pound of steam. In

our reheat superheater about one-half a pound of hot gases is required per pound of steam, although this may vary somewhat, depending upon the quality of the steam which varies with the turbine load, so that there should not be a large drop in pressure on account of the friction of the steam flowing through, as above mentioned. This is especially important as larger quantities of steam flow through the reheat superheater than would normally be generated by a single boiler.

Also, by permitting the steam to enter the superheater at the bottom and rise through a plurality of tubes of large aggregate cross-sectional area that are heated through a considerable distance, as described, the draft effect of the rising steam is sufficient to compensate in large measure for inequalities and cause greater uniformity of distribution of steam through the tube, and the temperature increase as the steam rises aids the flow and tends to neutralize the friction.

The height of an ordinary superheater is not sufficient to produce any appreciable amount of draft caused by so-called "stack" effect, but with our device we find that the upward draft of the steam produced in the reheat superheater tubes is sufficient to overcome a considerable amount of steam friction in the tubes. This is especially noticeable at small loads, as the friction varies inversely as the square of the load. The friction at small loads is too small to be relied upon to produce uniform distribution of steam through the tubes. The draft effect due to the great vertical height of our superheater is, therefore, especially advantageous in aiding steam distribution through the tubes at loads where friction is not sufficient for this purpose.

We claim:

1. In a steam boiler, a first vertical flue disposed above the boiler heating surfaces and leading upwardly therefrom, a second vertical flue adjacent the first flue and having its upper portion connected to the upper portion of the first flue with a gas exit at the bottom of the second flue, a wall dividing said flues, a support for said wall disposed above said surfaces, and a steam superheater having tubes extending across the second flue with the steam inlet at the bottom and the steam outlet at the top of the second flue, with the superheater tubes arranged to lead the steam back and forth across the second flue to the steam outlet.

2. In a steam boiler, a first vertical flue disposed above the boiler heating surfaces and leading upwardly therefrom, a second vertical flue adjacent the first flue and having its upper portion connected to the upper portion of the first flue with a gas exit at the bottom of the second flue, a wall dividing said flues, a support for said wall disposed above said surfaces, and a steam superheater having

versely of the second flue, the legs of the second set of U-tubes being shorter than the legs of the first set of U-tubes and the first set of U-tubes extending into and transversely of the first flue.

9. In a steam boiler, a first vertical flue leading from the gas exit from the boiler heating surfaces, a second vertical flue adjacent the first flue and having its upper portion connected to the upper portion of the first flue with a gas exit at the bottom of the second flue, a superheater inlet manifold at the bottom of the second flue and a superheater outlet manifold at the top of the second flue, a supplemental manifold between said inlet and said outlet manifolds, said manifolds being positioned adjacent the wall of said second flue remote from said first flue, a first set of U-tubes connecting the outlet manifold and the supplemental manifold and a second set of U-tubes connecting the supplemental manifold and the inlet manifold and having a plurality of reverse bends, said tubes extending transversely of the second flue, the legs of the second set of U-tubes being shorter than the legs of the first set of U-tubes, and the first set of U-tubes extending into and transversely of the first flue and resting on the top of the wall between the flues.

10. In a steam boiler, a first vertical flue disposed above the boiler heating surfaces and leading upwardly therefrom, a second vertical flue adjacent the first flue and having its upper portion connected to the upper portion of the first flue with a gas exit at the bottom of the second flue, a wall dividing said flues, a support for said wall disposed above said surfaces, a superheater inlet manifold at the bottom of the second flue and a superheater outlet manifold at the top of the second flue, a supplemental manifold between said inlet and said outlet manifolds, said manifolds being positioned adjacent the wall of said second flue remote from said first flue, a first set of U-tubes connecting the outlet manifold and the supplemental manifold and a second set of U-tubes connecting the supplemental manifold and the inlet manifold, said tubes extending transversely of the second flue, the outer walls of the second flue being provided with doors, whereby the U-tubes may be withdrawn from and inserted into operative position.

11. In a steam boiler, a vertical flue connected to cause a downward flow of hot gases therethrough and disposed above the boiler heating surfaces, a superheater having tubes extending transversely of said flue and connected to cause a generally upward flow of the steam to be superheated, said superheater comprising an inlet, an outlet and a supplemental manifold at the side of the flue, U-tubes connecting the in-

let manifold and the supplemental manifold and U-tubes connecting the outlet manifold and the supplemental manifold.

12. In a steam boiler, a vertical flue connected to cause a downward flow of hot gases therethrough and disposed above the boiler heating surfaces, a superheater having tubes extending transversely of said flue and connected to cause a generally upward flow of the steam to be superheated, said superheater comprising an inlet, an outlet and a supplemental manifold at the side of the flue, U-tubes connecting the inlet manifold and the supplemental manifold and U-tubes connecting the outlet manifold and the supplemental manifold and doors in the wall between adjacent manifolds to provide access to the U-tubes connecting said manifolds.

13. In a steam boiler, a first vertical flue disposed above the boiler heating surfaces, a second vertical flue adjacent the first flue and having its upper portion connected to the upper portion of the first flue with a gas exit at the bottom of the second flue, a steam superheater having tubes extending across the second flue with the steam inlet at the bottom and the steam outlet at the top of the second flue, with the superheater tubes arranged to lead the steam back and forth across the second flue, a wall dividing said flues, and a hollow air-cooled girder supporting said wall.

14. In a steam boiler, a first vertical flue disposed above the boiler heating surfaces, a second vertical flue adjacent the first flue and having its upper portion connected to the upper portion of the first flue with a gas exit at the bottom of the second flue, a steam superheater having tubes extending across the second flue with the steam inlet at the bottom and the steam outlet at the top of the second flue, with the superheater tubes arranged to lead the steam back and forth across the second flue, a wall dividing said flues, and a hollow air-cooled girder supporting said superheater tubes and said wall.

15. In a steam boiler, a first vertical flue disposed above the boiler heating surfaces and leading upwardly therefrom, a second vertical flue adjacent the first flue and having its upper portion connected to the upper portion of the first flue with a gas exit at the bottom of the second flue, a wall dividing said flues, a support for said wall disposed above said surfaces, and a steam superheater having tubes extending across the second flue, said first named flue being provided with openings for introducing cold air therein.

16. In a steam boiler, a first vertical flue disposed above the boiler heating surfaces and leading upwardly therefrom, a second vertical flue adjacent the first flue and having its upper portion connected to the upper portion of the first flue with a gas exit at the bottom of the second flue, a wall dividing said flues, a support for said wall disposed above

- said surfaces, a steam superheater having tubes extending across the second flue, and a by-pass for gases between said flues, below said superheater.
17. In a steam boiler, a vertical flue connected to cause a downward flow of hot gases therethrough, and a superheater having tubes extending transversely of said flue and connected to cause a generally upward flow of the steam to be superheated, said tubes extending in a vertical plane a sufficient distance to produce an upward draft of steam in said tubes equivalent to a substantial part of the flow resistance of the steam, thereby to promote a flow of steam in the tubes.
18. In a steam boiler, a vertical flue connected to cause a downward flow of hot gases therethrough, and a superheater having tubes extending transversely of said flue and connected to cause a generally upward flow of the steam to be superheated, said tubes being of sufficient cross sectional area and extending a sufficient distance vertically to produce an upward draft in said tubes equivalent to a substantial part of the flow resistance of the steam, thereby to promote a flow of steam in the tubes.
19. In a steam boiler, a first vertical flue leading from the gas exit from the boiler heating surfaces, a second vertical flue adjacent the first flue and having its upper portion connected to the upper portion of the first flue, with a gas exit at the bottom of the second flue, and a steam superheater having tubes extending across the second flue with the steam inlet at the bottom and the steam outlet at the top of the second flue, with the superheater tubes arranged to lead the steam back and forth across the second flue, some of said tubes extending partially across said first flue.
20. In a steam boiler, a first vertical flue conducting gases upwardly therein, a second vertical flue adjacent the first flue and having its upper portion connected to the upper portion of the first flue, with a gas exit at the bottom of the second flue, and a steam superheater having tubes extending across the second flue with the steam inlet at the bottom and the steam outlet at the top of the second flue, with the superheater tubes arranged to lead the steam back and forth across the second flue, some of said tubes extending partially across said first flue.
21. In a steam boiler, a first vertical flue conducting gases upwardly therein, a second vertical flue adjacent the first flue and having its upper portion connected to the upper portion of the first flue, with a gas exit at the bottom of the second flue, a steam superheater having tubes extending across the second flue with the steam inlet at the bottom and the steam outlet at the top of the second flue, with the superheater tubes ar-
- ranged to lead the steam back and forth across the second flue, some of said tubes extending partially across said first flue, and a wall disposed between said flues and supporting the tubes extending into said first flue.
22. In a steam boiler, a first vertical flue conducting gases upwardly therein, a second vertical flue adjacent the first flue and having its upper portion connected to the upper portion of the first flue with a gas exit at the bottom of the second flue, a wall separating said flues, an air cooled girder disposed beneath said wall and supporting the same, a steam superheater having tubes extending across the second flue and adapted to lead the steam back and forth thereacross, some of said tubes extending partially into said first flue and supported on top of said wall, and means supporting the rest of said tubes from said girder.
23. In a steam boiler, a first vertical flue conducting gases upwardly therein, a second vertical flue adjacent the first flue and having its upper portion connected to the upper portion of the first flue, with a gas exit at the bottom of the second flue, a steam superheater having tubes extending across the second flue with the steam inlet at the bottom and the steam outlet at the top of the second flue, with the superheater tubes arranged to lead the steam back and forth across the second flue, some of said tubes extending partially across said first flue, and a partition separating said flues and supporting said last-named tubes.
24. In a steam boiler, a first vertical flue conducting gases upwardly therein, a second vertical flue adjacent the first flue and having its upper portion connected to the upper portion of the first flue, with a gas exit at the bottom of the second flue, a steam superheater having tubes extending across the second flue with the steam inlet at the bottom and the steam outlet at the top of the second flue, with the superheater tubes arranged to lead the steam back and forth across the second flue, and a partition of refractory material disposed between said flues, said tubes being arranged at right angles to said partition and some of them extending over the top of said partition into said first flue, said partition acting as a support for said last-named tubes.
